CLAIM

The ornamental design for a pet coat, as shown and described.

DESCRIPTION

FIG. 1 is a top, rear, right perspective view of a pet coat, showing my new design in a first configuration;

FIG. 2 is a top plan view thereof;

FIG. 3 is a left side view thereof;

FIG. 4 is a rear elevation view thereof;

FIG. 5 is a right side view thereof;

FIG. 6 is a front elevation view thereof; and,

FIG. 7 is a bottom plan view thereof.

The broken lines in the drawings depict portions of the pet coat that form no part of the claimed design.
